UNITED STATES PATENT OFFICE

158,946

COMBINED PEN AND PENCIL

Raymond Duelfer, Danbury, Conn., assignor to
The Risdon Manufacturing Company, Naugatuck,
Conn., a corporation of Connecticut

Application April 5, 1950, Serial No. 8,982

Term of patent 14 years

(Cl. D74—24)

To all whom it may concern:

Be it known that I, Raymond Duelfer, a citizen of the United States, residing at Danbury, State of Connecticut, have invented a new, original, and ornamental Design for a Combined Pen and Pencil, of which the following is a specification, reference being had to the accompanying drawing, forming a part hereof.

The single figure of the drawing is a perspective view of the combined pen and pencil embodying my new design.

I claim:
The ornamental design for a combined pen and pencil, as shown.

RAYMOND DUELFER.
